UNITED STATES PATENT OFFICE.

JACOB DASHEW, OF BALTIMORE, MARYLAND.

SEWING-MACHINE.

1,116,679.

Specification of Letters Patent. Patented Nov. 10, 1914.

Application filed January 18, 1914. Serial No. 312,394.

To all whom it may concern:

Be it known that I, JACOB DASHEW, a citizen of the United States, residing at Baltimore, in the State of Maryland, have invented certain new and useful Improvements in Sewing-Machines, of which the following is a specification.

This invention relates to improvements in sewing machines, and especially to that class in which the needle has a lateral, as well as a vertical, reciprocal motion, for the purpose of forming a staggered, zig-zag, or other fancy stitch.

The object of the invention is to so arrange the parts that the stitching may be done in close places, such as sewing labels on the inside of pockets, etc.

The invention consists of the novel construction and arrangement of the parts and combination of parts hereinafter more fully set forth in the following specification and pointed out in detail in the appended claims.

In the accompanying drawings,—Figure 1 is a side elevation of my invention, the lower portion of which is in vertical section and showing the operating parts therein. Fig. 2 is a detail plan view of the vertical horn with the plate removed and showing the shuttle and feed foot. Fig. 3 is an end view of Fig. 1; the horn being in vertical section and showing the mechanism for operating the shuttle and feed foot; the plate on the front of the head being also removed. Fig. 4 is a detail plan view of the horn with the plate thereon and showing the feed foot projecting therethrough. Fig. 5 is a modification in the mounting of the shuttle.

Referring to the accompanying drawings, forming part of this specification, and in which like reference numerals designate like parts through the several views thereof, 1 designates the base of the machine which is provided at one side with a vertical horn 2 and on the other side with a vertical upright portion 3 having an arm 4 provided on its outer end with a head 5. The main shaft 6 has a pulley 7 on its outer end, to which power is transmitted from any suitable source. This main shaft 6 projects through the arm 4 and has a disk 8 on its inner end to which is pivoted one end of the rod 9 the other end of which latter is pivoted to the collar 10. The said collar 10 being fast on the needle bar 11 the latter, and consequently the needle, will be

reciprocated vertically as the disk 8 is revolved with the main shaft 6. In the side of the arm 4 is mounted a disk 12 having a cam-slot 13 in the face thereof and a gear-wheel on the inner end in mesh with the gear-wheel 14 which latter is fast on the main shaft 6. The grooved lever 15 is pivoted at 16 to the arm 4 and has a roller 17 projecting therefrom which fits into the cam-slot 13. The rod 18 has one end adjustably connected to the lever 15 and the other end connected to the frame 19 in the head 5. This frame 19 is pivoted at 20, 20, to the head 5. The revolution of the cam-disk 12 causes the lever 15 to rock on its pivot 16 imparting a lateral reciprocal motion through the rod 18 to the frame 19, through which latter the needle-bar 11 projects, thus also imparting a lateral reciprocal motion to the needle bar and consequently to the needle. It will thus be seen that the needle has a lateral and a vertical reciprocal motion. The main shaft 6 is also provided with a beveled gear wheel 21 which meshes with the beveled gear wheel 22 on the upper end of the vertical shaft 23 which latter is also provided with a beveled gear wheel 24 in mesh with the beveled gear wheel 25 on one end of the shaft 26. On the other end of the shaft 26 is a gear wheel 27 in mesh with the gear wheel 28 on one end of the shaft 29, the other end of the shaft 29 being provided with a beveled gear wheel 30 in mesh with the beveled gear wheel 31 on the lower end of the shaft 22 the upper end of which latter projects through the bearing 33 and carries the revolving hook 34 on its upper end. Thus it will be seen that a rotary motion is imparted to the revolving hook 34, through the mechanism just described, from the main shaft 6. The rock shaft 35 has a rock arm 36 projecting therefrom, the outer end of which latter is secured to one end of the lever 37. This lever 37 is pivoted to the lower end of the feed-bar 38 and has its other end bifurcated to receive the end of the arm 39 projecting from the short rock-shaft 40. The said feed bar 38 has the usual foot 41 on its upper end and is pivoted to the boss 42 projecting from the horn 48, and has an elongated slot 43 to allow it to be operated up and down as well as to rock on said boss 42. The shaft 110 35 is rocked by means of a bell-crank lever 44 the bifurcated end of which fits over a

cam 45 on the shaft 26, the upwardly-projecting end of said bell-crank lever 44 being connected to a rod 46 which extends across to an arm on said shaft 35. The 5 rocking of the shaft 35 in turn rocks the feed-bar 38 which gives the lateral reciprocal motion to the foot 41. The short rock-shaft 40 is rocked by means of a cam on the shaft 26 over which the bifurcated end of 10 the arm 47 projects. The rocking of the shaft 40 imparts a vertical reciprocal motion to the foot 41 through the arm 39 and levers 37 and 38.

It will be seen that by having the revolving hook and feed operated in the vertical horn, a coat, or other garment, may be slipped over said horn in such a manner as to allow the operator to sew in close places, such as coat pockets, where it is impossible to operate the usual flat base machines.

In Fig. 5 I have shown a modification in which the revolving hook 49 is placed on a vertical plane.

25 Having thus described my invention, what I claim is:

1. In a sewing machine the combination of a base, a vertical work supporting horn projecting upwardly from one side of said 30 base, an arm projecting from the opposite side of said base and extending over said horn, a main shaft mounted in said arm, a needle bar mounted in the outer end of said arm and adapted to be operated vertically by said main shaft, means connecting the needle bar with said main shaft for operating the needle laterally, a vertical shaft in mesh with the main shaft; a shaft 26 having one end in mesh with the 35 said vertical shaft and the other end provided with a gear-wheel, a shaft 29 having one end in mesh with the shaft 26 and having a beveled gear wheel on the other end, a vertical shaft 32 having a gear wheel on its lower end in mesh with the gear wheel 70 on the shaft 29, a revolving hook on the upper end of the shaft 32, a rock shaft 35 having a rock arm 36, a lever 37 having one end connected to said rock arm 36 and its opposite end bifurcated, a feed bar having 75 its lower end pivoted to the lever 37 and its upper end carrying a feed foot, and a rock-shaft 40 having a bifurcated arm 47, a cam on the shaft 26 over which the bifurcated arm 47 fits.

In testimony whereof I affix my signature in presence of two witnesses.

JACOB DASHEW.

EMMA BEALE.

end, a vertical shaft 32 having a gear wheel on its lower end in mesh with the gear 45 wheel on the shaft 29, a revolving hook on the upper end of the shaft 32; a feed foot mounted in said vertical horn; and means connecting the main shaft with said feed foot for operating the same vertically and laterally.

2. In a sewing machine the combination of a base, a vertical work supporting horn projecting upwardly from one side of said base, an arm projecting from the opposite side of said base and extending over said horn, a main shaft mounted in said arm, a needle bar mounted in the outer end of said arm and adapted to be operated vertically by said main shaft, means connecting the needle bar with the main shaft for operating the needle laterally, a vertical shaft in mesh with the main shaft, a shaft 26 having one end in mesh with the said vertical shaft and the other end provided 60 with a gear-wheel, a shaft 29 having one end in mesh with the shaft 26 and having a beveled gear wheel on the other end, a vertical shaft 32 having a gear wheel on its lower end in mesh with the gear wheel 65 on the shaft 29, a revolving hook on the upper end of the shaft 32, a rock shaft 35 having a rock arm 36, a lever 37 having one end connected to said rock arm 36 and its opposite end bifurcated, a feed bar having 70 its lower end pivoted to the lever 37 and its upper end carrying a feed foot, and a rock-shaft 40 having a bifurcated arm 47, a cam on the shaft 26 over which the bifurcated arm 47 fits.
